(57) CLAIM

The ornamental design for a smokeless fire pit, as shown and described.

DESCRIPTION

FIG. 1 is an exploded front top left side perspective view for a smokeless fire pit, showing my new design in a disassembled configuration;

FIG. 2 is a rear top right side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof, right side elevational view being a mirror image;

FIG. 6 is a top plan view of FIG. 1 thereof;

FIG. 7 is a bottom plan view of FIG. 1 thereof;

FIG. 8 is a front top left side perspective view of FIG. 1 thereof, in an assembled configuration, wherein air ventilation grid has been removed; and,

FIG. 9 is a rear top right side perspective view of FIG. 1 thereof, in an assembled configuration, wherein the air ventilation grid has been shown and the lid has been removed.

The broken lines indicate unclaimed portions of the smokeless fire pit and form no part of the claimed design.
